UNITED STATES PATENT OFFICE

FREDERICK LAMATSCH, OF GRANTWOOD, NEW JERSEY, ASSIGNOR TO R. HOE & CO., INC., OF NEW YORK, N. Y., A CORPORATION OF NEW YORK

PLATE CLAMP

Application filed November 1, 1927. Serial No. 230,262.

This invention relates to certain improvements in plate clamps.

In printing practice where stereotype or similar plates are employed, the plates are clamped on the plate support by means of certain clamping devices which engage the edge of the plates and by which the plates are clamped or held against a suitable abutment so that the plates are rigidly held on the supports during the printing operation.

In printing certain products, as for instance papers, periodicals and the like, the plate supports are usually in the form of cylinders capacitated to carry four plates wide, that is, four plates extending across the cylinder. For clamping these plates, there is provided a central fixed rib and two movable clamps for clamping two plates on each side of this rib. One of these movable clamps is arranged to engage the inside edge of the outer plate on one end of the cylinder and the outside edge of the inner plate, the outside edge of the outer plate being engaged by the other movable clamp, this construction being duplicated on each end of the cylinder. In the production of certain products, it is frequently desirable to produce products having different widths. As for instance, it may be necessary to change from an arrangement for printing a product eight columns wide to an arrangement whereby a product nine columns wide may be printed. Such change in the width of the product necessitates a change in the position of the clamps engaging the plates.

It is the special object of the present invention to provide a simple arrangement whereby the position of the clamps may be quickly and readily changed so that the cylinder may be plated with plates differing by a column width, or any other predetermined width in a minimum amount of time.

A further object of the invention is to produce a simple and compact arrangement for effecting the desired change in the clamping arrangement and an arrangement which will effect the clamping of the inside plates where no outside plates are used.

With these and other objects not specifically referred to in view, the invention consists

in certain novel parts, arrangements and combinations which will be described in connection with the accompanying drawings and the novel features pointed out in the claims hereunto annexed.

55

In the drawings—

Figure 1 is a partly broken away sectional view of the plate cylinder showing the parts in position for clamping narrow plates;

Figure 2 is a similar view showing the parts in position when clamping wider plates;

Figures 3 and 4 are detail views in perspective showing the improved mechanism for quickly effecting the change in the position of the clamps.

65

Referring now to these drawings, the plate support is shown in the form of a cylinder 1, which is provided with the central fixed rib or margin bar 2, having the usual undercut clamping faces 3. This cylinder may be capacitated to carry four plates wide, and three such plates, 4, 5 and 6, are shown, the plates 5 and 6 abutting at their adjacent edges against the fixed stop 2.

70

The improved clamping mechanism is the same at each end of the cylinder, such mechanism being shown at the left hand end of the cylinder as clamping the plates 4 and 5.

75

This clamping mechanism includes a clamp block 7 having bevelled plate engaging faces 8, 9, the face 8 engaging the inner edge 10 of the outer plate 4, and the face 9 engaging the outer edge 11 of the inner plate 5. The outer edge of the outer plate 4 is clamped by a clamp block 12 having a bevelled face 13 engaging the bevelled outer edge 14 of the plate 4.

80

In the showing of Figure 1, the plates 4, 5 are relatively narrow plates. In the showing in Figure 2, the plates which are indicated by numerals 4', 5' and 6', are shown as relatively wider plates. In accordance with the invention, means are provided whereby the clamps may be readily and quickly arranged in adjusted position for clamping plates of different widths. While the specific embodiment of these means may be somewhat varied, such means will include spacing mechanism for the inner clamp block 7, by which

85

90

95

100

the position of the movable clamp on the cylinder is determined. As shown, the outer clamp block 12 is threaded on to the usual screw rod 15, this rod having a squared end 16 which may be turned through the use of a suitable tool, to cause a travelling movement of the clamp block 12. These parts, and other parts hereinafter referred to, are positioned in a groove or slot 17 formed in the cylinder wall.

The spacing mechanism is such that by a single movement the clamp block 7 may be permitted a sliding movement in the groove. As shown, this mechanism includes a push rod 18, preferably formed with a head 19 against which the clamp 12 may be moved for a purpose hereinafter referred to. This push rod is slidably supported so that it can be turned or rotated in a block 20 in the cylinder wall and its inner end beyond the block is flattened out as indicated at 21. This flattened end is arranged to engage a slotted member 22, carried by the block 7 before referred to, this slotted member being preferably separate from the block and secured thereto by a threaded shank 23 screwed into the block, a locking nut 24 being provided for locking the slotted member in position. This slotted member is formed with a deep groove or slot 24' and a shallower groove or slot indicated at 25. It will be observed that when the flattened end 21 is in the position shown in Figure 1, it can enter the narrow slot only and the block 7 is held in the position shown in Fig. 1; if the rod 18 is turned to the position shown in Figure 2, however, it can enter the deep slot 24' of the member 22. This permits the positioning of the block 7 further to the left as shown in that figure, thus permitting the positioning of the wider plate 5' on the support. With this construction, therefore, the clamp can be very quickly and easily adjusted to permit the employment of narrow or wider plates. It will be understood, of course, that suitable guides are provided for the block 7, such guides being indicated at 26.

Where two plates are on the support as shown in the figures, they are locked up by the clamp 12 engaging the outer plate. Where, however, only the inner plates 5, 5' are on the cylinder, the clamp is operated by the screw rod 15 until it engages the end 19 of the push rod 18, whereupon a further movement of the clamp locks up the plate by pushing the rod to the right. The clearance between the screw rod 15 and the rod 18, permits a movement of the clamp block 7 to the left to unlock the inner plate.

While the invention is shown and described in its preferred form, it will be understood that various changes may be made in the form of the spacing mechanism and its arrangement in the cylinder without depart-

ing from the invention as defined in the appended claims.

What I claim is—

1. In a plate clamp, the combination of a plate support, a movable clamp block engaging the outer edge of an inner plate, a member carried by the block and having a plurality of seats of different depths, a rotary member having means for engaging one or the other of the seats to provide for holding the clamp block in different positions on the plate support, and means for locking up the plate.

2. In a plate clamp, the combination of a plate cylinder, a movable clamp block engaging the outer edge of an inner plate, a member carried by the block and having a plurality of seats of different depths, a rod having a flattened end for engaging one or the other of the seats depending on the position to which the rod is turned and means for locking up the plates.

3. In a plate clamp, the combination of a plate cylinder, a movable clamp block on the cylinder and rotary spacing means including a rod having a plurality of operating faces and a cooperating socket having seats of different depths with which the rod cooperates for holding the clamp in different positions widthwise of the cylinder.

4. In a plate clamp, the combination of a plate support, a movable clamp on the support, and rotary spacing means including a rod having a plurality of operating faces and a cooperating socket having seats of different depths with which the rod cooperates for holding the clamp in different positions on the support.

5. In a plate clamp, the combination of a cylinder, a movable clamp on the cylinder engaging the outer edge of an inner plate, a push rod having a plurality of engaging faces, a member on the clamp having seats of different depths engageable by the rod, a second clamp, and means for moving the second clamp into engagement with the rod.

6. In a plate clamp, the combination of a plate cylinder, a movable clamp block on the cylinder, a member carried by the block and slotted two ways, one slot being deeper than the other by an amount equal to the difference in width of two plates, and a rod having an end capacitated to engage one or the other of the slots.

7. In a plate clamp, the combination of a plate cylinder, a movable clamp on the cylinder provided with a member having a plurality of seats, and a rotatable push rod having adjustable sliding engagement with either of the seats depending on the position to which the rod is turned for holding the clamp in different positions widthwise of the cylinder.

8. In a plate clamp, the combination of a plate cylinder, a movable clamp on the cylinder provided with a member having a plural-

ity of seats, a rotatable rod having adjustable sliding engagement with either of the seats depending on the position to which the rod is turned, a second clamp, and means for moving the second clamp into engagement with the rod.

In testimony whereof, I have hereunto set my hand.

FREDERICK LAMATSCH.
